FRAME FOR MAKING FRINGE

Jeannette L. Webb, P.O. Box 287,
Madison, N.J. 07940

Filed Jan. 30, 1973, Ser. No. 327,959

Term of patent 14 years

Int. Cl. D15—06

U.S. Cl. D3—19 A

FIG. 1 is a front perspective view of a frame for making fringe showing my new design.

FIG. 2 is a rear perspective view thereof.

FIG. 3 is a front perspective view thereof with the slide portion in a fully extended position.

FIG. 4 is a cross-sectional view taken on the line 4—4 of FIG. 1.

I claim:

The ornamental design for a frame for making fringe, as shown and described.
